UNITED STATES PATENT OFFICE.

HENRY F. BECHMAN, OF BATTLE CREEK, MICHIGAN, ASSIGNOR, BY MESNE ASSIGNMENTS, TO DETROIT TRUST COMPANY, TRUSTEE, A CORPORATION OF MICHIGAN.

FOUR-PAGE-WIDTH TUBULAR PLATE PRESS.

Application filed March 6, 1920, Serial No. 363,348. Renewed March 31, 1922. Serial No. 548,444.

To all whom it may concern:

Be it known that I, HENRY F. BECHMAN, a citizen of the United States, residing at Battle Creek, in the county of Calhoun and State of Michigan, have invented certain new and useful Improvements in Four-Page-WIDTH TUBULAR PLATE PRESSES; and I hereby declare that the following is a full, clear, and exact description thereof, reference being had to the accompanying drawings, which form part of this specification.

This invention is an improvement in rotary web printing presses of the single page tubular plate type disclosed in my Patents Nos. 867,230 of October 1, 1907, and 1,240,008, of September 11, 1917. The object of this invention is to produce a press, such as shown in my first mentioned patent, capable of printing a four-page wide web, as suggested in my second patent, but without the necessity of employing "staggered" impression mechanisms; and I accomplish this by so constructing the type-cylinders of the press that they are enabled to each carry four or more single-page tubular plates without "springing" or bulging when rotated at high speed or under impression pressure.

In this invention each type cylinder is provided with an auxiliary central or intermediate bearing whereby such cylinder is effectually prevented from springing or bulging at high speed, or from yielding under high impression pressures; and thereby I am able to construct a single-page tubular plate press in which each plate cylinder can carry four or more single-page tubular plates arranged end to end; and by which four or more page wide webs may be printed without slitting such webs prior to printing; and in which equal margins can be left between the adjacent page side by side impressions transversely of the web.

This invention further enables a single-page-tubular-plate-cylinder to be made four or more pages wide without multiplication of printing mechanisms, such as is required with the staggered arrangement shown in my Patent No. 1,240,008; and without requiring any greater number of printing mechanisms or inking mechanisms to print a four or more page wide web, than is required to print a two page wide web as shown in my Patent No. 867,230.

Minor objects and advantages of the invention will be hereinafter referred to in the detailed description of the invention.

I will explain the invention with reference to the accompanying drawings which illustrate the novel construction of the tubular plate cylinders, and the bearings thereof and sufficient of the cooperating parts of a printing press to enable others skilled in the art to adapt and use the invention. The essentials of the invention and the novel features of construction and novel combinations of parts for which protection is desired are summarized in the claims.

In said drawings:

Fig. 1 is a top plan view of part of a web printing press showing a single page tubular plate cylinder adapted to carry four single page tubular plates, an impression cylinder arranged to coat therewith; and means for supporting said cylinders.

Fig. 2 is a sectional view on the line 2—2, Fig. 1, and conventionally indicating an inking mechanism.

Fig. 3 is an enlarged longitudinal section through part of the plate cylinder and its intermediate bearing on the line 3—3, Fig. 2.

Fig. 4 is a transverse section on the line 4—4, Fig. 3.

Fig. 5 is a perspective view of an intermediate plate-cylinder-bearing detached.

The plate cylinder 1 is adapted to carry four or more single-page-tubular plates P, such as shown in my Patent No. 979,919 of December 27, 1910; four of such plates being shown. This plate cylinder 1 is journaled in end bearings 1^a which are so constructed as to permit the single page tubular plates P to be slipped endwise over the bearing into position on the plate cylinder, or off the plate cylinder, as explained in said Patent No. 979,919.

Beside the plate cylinder 1 and cooperating therewith is an impression cylinder 2, which is suitably journaled in or on the main frame, and is adapted to coat with the plates on the plate cylinder to print a web or sheet of paper passed therebetween.

The plate and impression cylinders are intergeared in any suitable way so that they will rotate at the proper relative peripheral speeds and in proper time. For example they might be intergeared as indicated in my Patent No. 1,223,025 of April 17, 1917.

Preferably the drive is of such construction that the plates P can be slipped endwise over the bearings and on or off either or both ends of the cylinder 1. The particular gearing between, or mechanism for driving, such cylinders forms no part of the present invention and is not claimed herein.

Owing to the small diameter of the plate cylinders for single-page tubular-plates, at 10 high speeds such cylinders if more than two pages long have a tendency to spring or bulge at the center, such tendency being accentuated by the impression pressure, and this seriously affects the operation of the 15 printing mechanism and the uniformity of the product. I found that such plate cylinders made out of solid hard steel if more than two pages long would thus spring at high speeds. Many attempts have been made 20 to overcome this difficulty, but heretofore none have been practically satisfactory; but by my present invention I have provided a means to overcome or prevent such springing or yielding of such plate cylinders and 25 am enabled to make them four or more pages wide and to hold them accurately to their work, and prevent springing thereof either at high speeds or under high impression pressures.

30 In the present invention each plate cylinder 2 for a four or more page wide press is made in two or more transverse sections. In the drawings the plate cylinder is shown as formed of two similar transverse sections 35 1^a, 1^a (see Fig. 3) which extend from the center outwardly. The inner ends of these sections 1^a are axially bored to receive a steel shaft 3, which is disposed axially of the sections 1^a, 1^a and connects and supports the 40 inner ends thereof. This shaft 3 is journaled in a cylindric bearing 4, which has a smooth running fit against the ends of the cylinder sections 1^a.

45 The bearing 4 is connected by a narrow web portion 4^a with a base portion 4^b and the bearing web and base may be formed integral of steel, or other suitable metal, as indicated in Fig. 5; the web 4^a can be formed by cutting circular grooves 4^c, in opposite 50 sides of the block, sufficiently wide to afford clearance for the portions of the inner ends of the sections 1^a, or parts connected therewith, which overlap the ends of the bearing 4 as indicated in Fig. 3. This web connection between the bearing 4 and the base 4^b is very strong and stiff and is not liable to spring or deflection because of its peculiar shape. To facilitate assembling the parts the bearing 4 might be cut in half as indicated in Fig. 4, the detachable half 4^x of the bearing being rigidly fastened to the other half of the bearing by tap bolts 4^e, as indicated in the drawing.

55 The bearing 4 is supported directly in the axial line of the plate cylinder by any suitable

means. Preferably it is fastened to a brace or tie member 6 that extends between and is secured to the opposite side frames of the machine adjacent the plate cylinder (see Figs. 1 and 2), the base 4^b of the bearing being secured to the inner side of this tie bar by any suitable means, bolts 4^a being indicated in the drawings.

60 Preferably tie 6 is cast hollow and has upper, lower and intermediate horizontal 75 walls 6^a, 6^b, 6^c, as indicated in Figs. 2 and 4; and I prefer to make the tie about four times as wide as the diameter of the plate cylinder. This tie 6 is secured between the side frames of the press in any suitable manner, and preferably so that it lies practically horizontal and in the plane of the axes of the cylinders 1 and 2 and its inner side closely adjacent the plate cylinder 2, so that the impression thrust of the impression cylinder 2 is transmitted through the plate cylinder 1 and bearing 4 directly to the tie 6; such tie being sufficiently strong to withstand any practical impression pressure 85 without deflection.

90 The large tie 6 not only serves to support the intermediate bearing of the plate cylinder, but also serves as a convenient support for the inking mechanisms for the plate cylinder. The ink fountain, the ink drum 95 and system of inking rollers for the plate cylinder 1 may all be mounted upon the related tie 6 as indicated in Fig. 2. The inking mechanism may be like that shown in my Patent No. 1,301,091, of April 22, 1919, 100 or of any other suitable kind and forms no part of the present invention.

105 The ends of the shaft sections 1^a may be recessed to receive the bushing, or the adjacent ends of the sections 1^a may be reduced as at 1^e to the diameter of the bushing 4 and hardened steel bands 5 may be fitted onto the reduced ends 1^e of the sections 1^a and secured thereto by any suitable means, said bands 5 projecting over the adjacent ends 110 of the bearing 4 and almost contacting with the web 4^a of the bearing, so that the inner ends of the adjacent plates P project over the ends of the bearing 4 and are only separated by the usual and necessary margin required between side by side impressions on the web or sheet.

115 The bands 5 are preferably made of similar opposite halves and securely fastened to the reduced ends 1^e of the parts 1^a by screws 120 5^a; and these bands 5 may be provided with internal annular ribs 5^b engaging corresponding annular grooves in the reduced inner ends 1^e of the sections 1^a. The inner ends of the bands 5 or the sections 1^a may be provided with exterior flanges 5^c against which the inner ends of the two inner tubular plates P abut, as indicated in the drawing.

125 The plate-cylinder is thus provided at the point where it is most liable to spring when 130

rotated at high speed or yield under impression pressure with a solid substantial bearing by which the plate cylinder is absolutely prevented from springing or yielding.

- 5 With this invention I am able to build tubular page plate cylinders four or more pages in length and to successfully operate them at any desired speed without any disadvantageous results or effects on the product due to springing or yielding of such cylinders; as the tendency of the long cylinder of small diameter to spring at high speed or to yield under impression pressure is entirely overcome.
- 10 Furthermore I am enabled to make single page tubular plate cylinders four or more pages wide, and to slip the tubular plates thereon either from one or both ends, and to have the plates spaced equally apart, and yet provide an intermediate bearing for the plate cylinder, which bearing is supported exterior to the plate cylinder by a web which is less in width than the necessary margin between adjacent impressions on the web.
- 15 Furthermore by this invention with one tubular impression cylinder I can print a web four or more pages wide before slitting it. Further by printing such wide webs I am enabled to greatly reduce the number 20 of printing couples and inking mechanisms required in the forms of presses shown in my Patents Nos. 867,230 and 1,240,008 aforesaid.

This invention also enables me to print 25 a four or more page wide web with single-page-tubular plates, without severing the web prior to the printing thereof, which is a great advantage, insuring uniformity of travel of the web and proper positioning of 30 the various impressions upon the web.

In the drawings I have simply shown one printing couple comprising a plate and impression cylinder and connecting mechanism, as the present invention relates particularly 35 to the construction and support of the plate cylinder. In a perfected mechanism, such plate and impression cylinders will be duplicated; and in a large press any desired number of such printing couples, or perfecting 40 mechanisms thereof can be employed according to the desired total capacity of the press.

What I claim is:

1. A cylinder for printing presses, comprising adjacent sections arranged end to end, each section adapted to carry a removable plate, and a bearing member interposed between the adjacent ends of said sections having a narrow supporting web of less width than the margin between adjacent impressions extending out between the sections.

2. A cylinder for printing presses, comprising shaft sections arranged end to end each section adapted to carry a removable plate; and a bearing member interposed between and supporting the adjacent ends of

said sections and having a narrow supporting web of less width than the margin between adjacent impressions on the paper produced by adjacent plates, said supporting web extending out between the sections, the inner ends of the cylinder sections projecting over the ends of the bearing member.

3. A cylinder for rotary printing presses, comprising adjacent sections arranged end to end, each section adapted to carry a removable plate; a bearing member concealed between the ends of and supporting said sections; said member having a support thinner than the required margin between adjacent plates on the cylinder and projecting between the sections and connected to a suitable fixed support.

4. In combination a cylinder for rotary web printing presses formed of adjacent sections arranged end to end; each section adapted to carry a removable plate; a stub shaft between and connecting the inner ends of said sections; a bearing member between the ends of the cylinder sections and supporting said shaft; said member having a supporting web thinner than the required margin between adjacent plates on the cylinder and projecting between the sections and connected to a suitable support, substantially as described.

5. In combination a cylinder for single-page-tubular-plate rotary web printing presses comprising adjacent sections arranged end to end each section adapted to carry a removable plate; a stub shaft between and connecting the inner ends of said sections; a bearing member between the ends of the cylinder sections and supporting said shaft; said member having a supporting web thinner than the required margin between adjacent plates on the cylinder and projecting between the sections and connected to a suitable support, the inner ends of the cylinder sections being recessed to accommodate the ends of the bearing member.

6. In combination a cylinder for printing presses, comprising end to end sections; a bearing member interposed between the adjacent ends of said sections and having a narrow supporting web extending out between the sections and attached to a rigid support, and annular bands fitted to the inner ends of the cylinder sections and projecting over the ends of the bearing member, substantially as described.

7. In combination a cylinder for printing presses, comprising end to end sections; a bearing member interposed between the adjacent ends of said sections and having a narrow supporting web of less width than the margin between adjacent impressions on the paper produced by adjacent plates, and extending out between the sections and attached to a rigid support; and annular bands fitted to the reduced ends of the cylinder

- sections and projecting over the ends of the bearing member and closely adjacent the supporting web of such member.
8. In combination a cylinder for printing presses, comprising end to end sections; a bearing member interposed between the adjacent ends of said sections and having a narrow supporting web extending out between the sections and attached to a rigid support, the inner ends of said cylinder sections being reduced adjacent the bearing member; and annular bands fitted to the reduced ends of the cylinder sections and projecting over the ends of the bearing member and closely adjacent to the supporting web of such member.
9. In combination a cylinder for single page tubular plate rotary web printing presses, comprising end to end sections; a bearing member interposed between the adjacent ends of said sections and having a narrow supporting web of less width than the margin between adjacent impressions on the paper produced by adjacent plates, and extending out between the sections and attached to a rigid support; the inner ends of the cylinder sections being reduced adjacent the bearing member; and annular bands fitted to the reduced ends of the cylinder sections and projecting over the ends of the bearing member closely adjacent to the supporting web of such member.
10. In combination a cylinder for rotary web printing presses, comprising similar end to end sections each section adapted to carry a removable plate; a stub shaft between and connecting the inner ends of said sections; a bearing member fitted between the ends of the cylinder sections and supporting said shaft and having a supporting web thinner than the required margin between adjacent plates on the cylinder projecting between the sections and connected to a suitable support.
11. In combination a cylinder for rotary web printing presses formed of similar transverse sections; a stub shaft between and connecting the inner ends of said sections; a bearing member fitted between the ends of the cylinder sections and supporting said shaft; said member having a supporting web thinner than the required margin between adjacent plates on the cylinder, said web projecting between the sections and connected to a suitable support; and annular bands fitted to the ends of the cylinder sections and projecting over the ends of the bearing member closely adjacent to the supporting web of such member.
12. A cylinder for single page tubular plate rotary web printing presses, comprising similar end to end sections each section adapted to carry a removable plate; a stub shaft between and connecting the inner ends of said sections; a bearing member fitted between the ends of the cylinder sections and supporting said shaft, the inner ends of the cylinder sections projecting over the ends of the bearing member; said bearing member having a supporting web thinner than the required margin between adjacent plates on the cylinder and projecting between the sections and connected to a suitable support.
13. In combination a cylinder for single page tubular plate rotary web printing presses, comprising similar end to end sections; a stub shaft between and connecting the inner ends of said sections; a bearing member fitted between the ends of the cylinder sections and supporting said shaft; said bearing member having a supporting web thinner than the required margin between adjacent plates on the cylinder and projecting between the sections and connected to a suitable support; the inner ends of the cylinder sections being reduced adjacent the bearing member; and annular bands fitted to the reduced ends of the cylinder sections and projecting over the ends of the bearing member closely adjacent to the supporting web of such member.
14. A bearing member having a cylindric longitudinally divided journal portion, concealed bolts uniting the parts of said journal portion a base portion, a narrow web connecting the cylindric portion with the base portion, the journal portion being separated from the base portion at each end by curved grooves or channels, the web portion separating such grooves and curved correspondingly with the curvature of the grooves.
15. In combination a cylinder for web printing presses, comprising similar sections arranged end to end; a stub shaft or journal connecting the inner ends of the sections; an annular bearing member fitted between the ends of the cylinder sections and supporting said shaft; said member having a supporting web thinner than the required margin between adjacent plates on the cylinder and projecting between the sections and connected to a suitable support; and annular bands fitted to the ends of the cylinder sections and projecting over the ends of the bearing member closely adjacent the supporting web of such member, said bands having ribs engaging corresponding grooves in the reduced ends of the sections.
16. In combination a single page tubular plate cylinder comprising similar sections arranged end to end; a stub shaft or journal connecting the inner ends of the sections; the inner ends of the cylinder sections being reduced; an annular bearing member fitted between the ends of the cylinder sections and supporting said shaft; said member having a supporting web thinner than the required margin between adjacent plates on the cylinder and projecting between the sections and connected to a suitable support; and annular

bands fitted to the reduced ends of the cylinder sections and projecting over the ends of the bearing member closely adjacent the supporting web of such member said bands having ribs engaging corresponding grooves in the reduced ends of the sections.

17. A cylinder for printing presses, comprising adjacent cylindric sections end to end, each section adapted to carry a removable plate and a supporting member for said sections extending out between the adjacent ends of said sections and of less width than the required margin between the impressions produced by the adjacent plates on the adjacent ends of said sections.

18. A cylinder for printing presses, comprising end to end sections, each section adapted to carry a removable plate, a journal member between said sections, and a supporting member engaging said journal to support the adjacent ends of said sections, and extending out between the sections, said supporting member being of less width than the margin between adjacent impressions on the paper produced by the plates on the adjacent ends of said sections.

19. In a web printing press the combination of an impression cylinder; a plate cylinder comprising adjacent sections end to end, each section adapted to carry a removable plate; and a supporting member for said sections extending out between the adjacent ends of said sections and permitting a wide web to be fed between said cylinders prior to slitting the web.

20. In a web printing press the combina-

tion of an impression cylinder; a plate cylinder comprising end to end sections, each section adapted to carry a removable plate; a stub shaft connecting said sections and a supporting member extending out between the sections; whereby a wide web can be passed between and printed by said sections prior to slitting the web.

21. In a web printing press the combination of an impression cylinder; a plate cylinder comprising adjacent sections end to end, each section adapted to carry a removable plate; and a supporting member for said sections extending out between the adjacent ends of said sections and of less width than the required margin between adjacent impressions produced on the web, whereby a wide web can be fed between said cylinders prior to slitting the web.

22. In a web printing press the combination of an impression cylinder; a plate cylinder comprising end to end sections, each section adapted to carry a removable plate; and a stub shaft connecting said sections and a supporting member interposed between the adjacent ends of said sections and supporting said shaft and extending out between the sections, said bearing member being of less width than the margin between adjacent impressions on the web, whereby a wide web can be fed between said cylinders prior to slitting the web.

In testimony that I claim the foregoing as my own, I affix my signature.

HENRY F. BECHMAN.
